(57) **CLAIM**

The ornamental design for a cartridge for printer, as shown and described.

DESCRIPTION

FIG. 1 is a front perspective view of a cartridge for printer, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof; and,

FIG. 8 is an exploded front perspective view thereof.

References to "side", "top", and "bottom" in the figure descriptions are not meant to require certain in-use orientation; a cartridge for printer according to the claimed design may be used in any orientation. The broken lines in the figures show portions of the cartridge for printer which form no part of the claimed design.
